UNITED STATES PATENT OFFICE.

CHARLES NORMAN PRATT, OF WAWASET, PENNSYLVANIA.

WAGON-LOADING DEVICE.

1,335,699.

Specification of Letters Patent. Patented Mar. 30, 1920.

Application filed October 27, 1916. Serial No. 128,096.

To all whom it may concern:

Be it known that I, CHARLES NORMAN PRATT, a citizen of the United States, residing at Wawaset, in the county of Chester and State of Pennsylvania, have invented new and useful Improvements in Wagon-Loading Devices, of which the following is a specification.

This invention relates to wagon loaders. 10 The object of the invention is to provide means for loading the contents of railway cars into wagons, without the use of shovels, or other manually operated means.

Another object of the invention is to 15 provide means for quickly loading wagons or other vehicles from railway cars without any waste of material, means being provided whereby contents of the cars are directed into the wagon and controlled when the said wagons have become filled, said means comprising a hopper provided with a well or depression therein and an outlet opening therefor by means of which the contents of the hopper may be directed and controlled.

25 A further object is to provide a baffle board arranged within said well or depression above the outlet opening and hingedly connected along one edge thereof to one of the walls of the depression and novel adjusting means hingedly connected at the 30 opposite edge of the board for adjusting the angle of the same, the location of said adjusting means providing means for strengthening the board along its free edge so as to 35 obviate the danger of breakage due to the contact of the material therewith.

A further object of the invention is to 40 provide an apparatus of this class which is of cheap and simple construction and which may be operated by one man.

With the above objects in view the invention consists of a preferably rectangular casing forming a hopper for the reception of the contents of a railway or other car, outlets 45 to the said hopper for directing the contents into the body of a wagon, inclines for directing the contents through the outlets, the said inclines being provided with removable bottoms whereby the contents may be screened 50 as it is loaded, adjustable baffle boards for directing the contents to the said screens, and spring actuated slides for the said outlets.

In the drawings:

55 Figure 1 is an end elevation of a railway car of the gondola type with the improved

wagon loader in position, and illustrating a portion of the wagon beneath the said loader ready to be loaded;

Fig. 2 is a top plan view of the loader; 60

Fig. 3 is an end elevation of the same;

Fig. 4 is a central longitudinal sectional view;

Fig. 5 is a detail view of one of the removable screens; and 65

Fig. 6 is a detail view of one of the removable bottom boards to be used in place of the screen.

In the practical embodiment of the invention the same consists of a preferably rectangular casing 1, of a size sufficient to be placed transversely beneath a railway car in a manner to rest upon the traction rails.

The casing or box 1, is provided with a floor from which extends downwardly through 70 openings arranged in spaced relation, hoppers A and B that are arranged in such spaced relation as to provide beneath the floor and the rails upon which the latter rests, a balanced structure. The casing 1 is 75

also provided with detachable flared sides 2. Each hopper is provided with outlet openings 3, surrounded by a flange collar 4 by means of which a flexible pipe (not shown) 80

may be attached for the purpose of directing material from the hopper into a wagon or other receptacle, should such receptacle be located any distance beneath the car. The 85

openings 3 are adapted to be closed by the slides 5, and are held in such closed position by means of springs 6 attached to the 90

end of the hopper and to the slide. A chain or other flexible member 7 is also attached to the slide, and is passed over a sheave 8 to provide means for manually opening the 95

slide to permit the contents of the hopper to pass through the opening 3. For the purpose of directing the material to the openings 3 the said openings are located in the vertical face of a well or depression 10

formed in the bottom of the hopper. This well is provided with an inclined wall 11, opposite the vertical wall 9 so that the material will be fed by gravity through the 100 opening 3. The inclined wall 11 is provided with an opening 12 into which there is

fitted one or more screens 13 of wire mesh. These screens may have a mesh of varying dimensions for the purpose of screening the material as it is delivered from the hopper to prevent a second handling for this purpose, the size of the mesh used depending 105

110

upon whether the material is crushed stone, coal or ashes, etc.

Located at the top of the well 10 is a baffle board 14 extending transversely across the 5 hopper, and is hinged thereto by means of hinges 15 provided with loose pins 16, in order that said boards may be removed when handling material not necessary to screen. Pivottally attached to the boards 14 at their 10 edges opposite the hinges 15 are bars 17 having their ends provided with notches 18 to engage a stop 19 for the purpose of regulating the inclines of the baffle boards. If desired hooks attached to the baffle board 15 and engaging eyes upon the inside of the hopper may be substituted for the rod 17, it not being thought necessary to illustrate this obvious change. When it is unnecessary to screen the material being handled the 20 screens 13 may be removed from the inclined wall 11, and metal covered boards 20 substituted in order to close the opening 12.

It will be seen from the foregoing that the invention provides a simple and efficient 25 means for loading wagons or other receptacles from railway cars, in a quick and efficient manner, without waste of material or loss of time.

Various changes in the form and proportion 30 of the invention may be made as prop-

erly fall within the scope of the appended claim, and the right is reserved to make these changes.

Having described the invention, what is claimed, is:

A wagon loader comprising a casing of a size and shape to rest upon the traction rails beneath a railway car, a pair of spaced hoppers extending respectively in open relation to said casing and projecting downwardly to provide a balanced structure beneath the bottom of said casing and below the rails upon which the bottom of said casing rests, each of said hoppers being provided with a vertical wall having an opening 40 facing in one direction and an inclined wall having an opening facing in an opposite direction, a closure for each of said openings, and a screen for substitution for the closure in the opening in the inclined wall, 45 and a baffle board pivotally hung from the floor of the casing that normally lies in a vertical plane in flatwise relation with the vertical wall and that is arranged to be swung over the screen when the latter covers 50 its opening, to direct the flow of material from the casing thereon and means to hold said baffle board in adjusted position.

In testimony whereof I affix my signature.
CHARLES NORMAN PRATT.
